UNITED STATES PATENT OFFICE

162,683

MELON PLUGGER KNIFE

Frank M. Ono and Perry T. Oishi, Dayton, Ohio, assignors to Pearl M. Parrett, Dayton, Ohio

Application July 27, 1950, Serial No. 11,438

Term of patent 14 years

(Cl. D22—3)

To all whom it may concern:

Be it known that we, Frank M. Ono and Perry T. Oishi, citizens of the United States, residing at Dayton, State of Ohio, have invented a new, original, and ornamental Design for Melon Plugger Knife, of which the following is a specification, reference being had to the accompanying drawing, forming a part hereof.

The single figure is a perspective view of a melon plugger knife, showing our new design.

We claim:

The ornamental design for a melon plugger knife, as shown.

FRANK M. ONO.
PERRY T. OISHI.
